UNITED STATES PATENT OFFICE.

LUTHER T. SEAVER, OF MEDFORD, MASSACHUSETTS.

BLIND-AWNING.

SPECIFICATION forming part of Letters Patent No. 228,784, dated June 15, 1880.

Application filed January 2, 1880.

To all whom it may concern:

Be it known that I, LUTHER T. SEAVER, of 5
Medford, in the county of Middlesex and State
of Massachusetts, have invented certain new
and useful Improvements in Blind-Awnings,
of which the following is a specification.

My invention relates to that class of devices
whereby the ordinary window-blinds are so
constructed that they can be converted into
10 an awning in a moment, and at pleasure read-
justed, so that they can be opened and closed
to be used as blinds; and the invention con-
sists in the construction, combination, and ar-
rangement of pivoted pintle-rod with the
15 lower blind-hinges, as hereinafter more fully
described and set forth.

Figure 1 represents a perspective view,
showing blind-awnings constructed according
20 to my invention. Fig. 2 represents a similar
view of my invention as a window-blind.

A represents a window-casing of usual con-
struction, to which are hinged the blinds B B'
in a peculiar manner. To the upper ends of
the blinds are secured the hinges C C', the
25 upper ends of which are bent or curved out-
ward and provided with a hole, which fits upon
the curved hooks E of the hinges, so as to
permit the bottom of the blinds to be pushed
outward, as shown in Fig. 1. To the blinds
30 B B', near their lower ends, are secured the
hinges R by means of a pivot or screw, G,
which permits the said hinges R to turn in
moving the blinds outward, the tube or socket
H of the hinge R sliding outward upon the
35 pivoted pintle-rod K, which turn upon the
joint formed by the lower hook-support, L, of the
hinge, and permits the bottom of the blinds
B to be moved outward to form an awning,
they being first secured together in position by
40 a suitable fastener, N. The weighted catches
P being raised up, as shown by dotted lines
in Fig. 2, the flaps R of the hinges are per-

mitted to turn out of line with the blind-stiles,
as shown. If the said blinds B are forced or
pushed outward quickly, the tubes or socks- 45
ets H slide outward and upward upon the piv-
oted pintle-rod K. The extreme upper ends
of the rods K are curved, as shown, so as to
cause the sockets H to bind thereon and hold
the blinds B in the desired position to serve 50
as an awning, as illustrated in Fig. 1. Now,
if the blinds be drawn inwardly at the bot-
tom, the inclined lower ends of the flaps R of
the hinges come in contact with the end of
the catch P and raise the weighted or han- 55
dle end, as shown in dotted lines in Fig. 2,
the hinge-flap resumes its former position, the
catch P falls down so as to confine the flap R
between its projecting end and the projecting
end of the plate or clip T, when the blinds 60
may be opened or closed in the usual manner,
as shown in Fig. 2.

Thus I am enabled to convert the ordinary
window-blinds into awnings in a very cheap,
simple, and expeditious manner. 65

Having thus described my invention, what I
claim, and desire to secure by Letters Patent,
is—

1. In combination with a window-blind, B,
having the curved hook-hinge C E, the piv- 70
oted pintle-rod K, pivoted hinge R H, catch P,
and stop T, all constructed and arranged to op-
erate as described, whereby the blind can be
made to form an awning, as set forth.

2. In combination with a window-blind, B, 75
the elongated pivoted pintle-rod K and piv-
oted hinge consisting of the flap R, having
an inclined lower end and sliding tubular por-
tion H, and hook-support L, substantially as
and for the purposes set forth.

LUTHER T. SEAVER.
